UNITED STATES PATENT OFFICE.

HUGO BONNINGHAUSEN, OF DETROIT, MICHIGAN.

DESIGN FOR A BILLIARD-TABLE.

SPECIFICATION forming part of Design No. 19,560, dated January 7, 1890.

Application filed November 9, 1889. Serial No. 329,798. Term of patent 7 years.

To all whom it may concern.

Be it known that I, HUGO BONNINGHAUSEN, a citizen of the United States, and a resident of Detroit, in the county of Wayne and State of Michigan, have invented and produced a new and original Design for Billiard-Tables, of which the following is a specification, reference being had to the accompanying drawing, which forms a part thereof.

10 The figure is a perspective view of my newly-designed billiard-table.

In the drawing, A represents the side rail, and A' the end rails. These rails are composed each of one wide or deep panel, extending 15 its whole length and depth. These panels are surmounted by a wide cornice B, consisting of four members or moldings b a c e, of like or different curves or forms, as suits the taste of the maker. The style or form of these 20 moldings, being only a part of the ornamentation of the table, is not of the essence of my design; but the width of the cornice from the front to the rail or panel forming a part of the outline of the table is an essential factor 25 in my design. Each upper member projects over the one below until they extend outward under the cushion-rail C of the table. The cushion-rail C is about the same depth as the cushion-rail of the ordinary billiard-table.

30 The corner-pieces D D' and their cornices B' B' project outward from the side and end rails only far enough to mark the change and to define the side and end panels. The corner-piece forms the upper section of the table-

leg. The portion below the table, or the lower 35 section of the leg D', is at first of the same size and form as the upper section, and it retains this square form for about one-half of its length, when it gradually changes to a round at two-thirds of its length, and when 40 its diameter is least, at d. Thence it expands, retaining substantially its round form, until it rests on the square, broad, wide, and deep foot E. The vertical outline of the leg between the rail and the foot is a cyma-reversa 45 curve, and it is exceedingly graceful.

Any desired ornamentation may be used on the side and end panels or on the corner-pieces or legs or elsewhere on the table without interfering with my design, which does 50 not include such ornamentation. This presents to the eye a table in which all the parts harmonize and combine to produce in the mind the idea of a graceful and rich outline.

What I claim is—

The design for a billiard-table, consisting of the outline formed by the deep side and end panels, the wide and deep corner-pieces, the wide cornice surmounting the panels and corner-pieces, the rail above the cornice, the 60 legs in vertical outline a cyma-reversa curve, and the square foot, all substantially as shown and described.

HUGO BONNINGHAUSEN.
